US00D928716S

(12) **United States Design Patent** (10) Patent No.: **US D928,716 S**
(45) Date of Patent: **** Aug. 24, 2021**

(54) **CONNECTOR**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans** **Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/688,476**

(22) Filed: **Apr. 22, 2019**

Related U.S. Application Data

(63) Continuation of application No. 29/641,690, filed on Mar. 23, 2018, now Pat. No. Des. 846,502, which is

(57) **CLAIM**

The ornamental design for a connector, as shown and described.

DESCRIPTION

FIG. 1 is a top front perspective view of a connector showing our new design;

FIG. 2 is a bottom rear perspective view thereof;

FIG. 3 is a top view thereof;

FIG. 4 is a bottom view thereof;

FIG. 5 is a side view thereof;

FIG. 6 is another side view thereof;

FIG. 7 is a front view thereof; and,

FIG. 8 is a rear view thereof.

The broken lines in the figures show portions of the connector that form no part of the claimed design.

1 Claim, 1 Drawing Sheet

Related U.S. Application Data

a continuation of application No. 29/563,898, filed on May 9, 2016, now Pat. No. Des. 813,820, which is a continuation of application No. 29/502,958, filed on Sep. 22, 2014, now Pat. No. Des. 755,724, which is a continuation of application No. 29/485,445, filed on Mar. 19, 2014, now Pat. No. Des. 713,796, which is a continuation of application No. 29/455,174, filed on May 17, 2013, now Pat. No. Des. 705,176, which is a continuation of application No. 29/426,587, filed on Jul. 6, 2012, now Pat. No. Des. 684,539.
